(57) **CLAIM**

The ornamental design for a hinge boring bit, as shown and described.

DESCRIPTION

FIG. 1 is a perspective view of the hinge boring bit;
FIG. 2 is a plan view taken along the line of the cutting blade portion of the tool shown in FIG. 1;
FIG. 3 is a plan view taken along a line perpendicular to the cutting blade portion of the tool shown in FIG. 1;
FIG. 4 is a top view of the tool shown in FIG. 1; and,
FIG. 5 is a bottom view of the tool shown in FIG. 1.
The broken lines in the drawings depict unclaimed environmental subject matter.
